Attorney

UNITED STATES PATENT OFFICE.

WALKER MONROE, OF DETROIT, MICHIGAN.

DESIGN FOR A SASH-LOCK CAM.

SPECIFICATION forming part of Design No. 34,280, dated March 26, 1901.

Application filed February 26, 1901. Serial No. 49,006. Term of patent 7 years.

To all whom it may concern:

Be it known that I, WALKER MONROE, a citizen of the United States, residing at Detroit, in the county of Wayne, State of Michigan, have invented and produced a certain new and original Design for a Sash-Lock Cam, of which the following is a specification, reference being had therein to the accompanying drawings.

10 In the drawings, Figure 1 is an elevation of a sash-lock cam, showing my design. Fig. 2 is a cross-section thereof on line 2 2 of Fig. 1, and Fig. 3 is a longitudinal section on line 3 3 of Fig. 1.

15 Like letters of reference indicate like parts throughout the several figures of the drawings.

As shown in the drawings, the leading or material feature of my design consists of a 20 series of curved figures disposed radially to a point eccentric to a circular outline. The outline A is substantially circular and provided at one side with a handle portion A', having a curved outline merged into the periphery of the portion A. At the opposite side of the outline A a rectangular lug A²

is disposed, while eccentric to this outline a curved figure B appears. Extending radially from this figure B are a series of curved figures C, herein shown as composed of elliptical figures C', connected by circular figures C²; so as to form a radial line extending from the circular figure B to the outline A. These figures are varied in size to correspond with the varying distances between the figure B 35 and the outline A, as shown by the accompanying drawings. The handle portion is shown with a triangular-shaped figure D, adjacent to the circular outline A, and at its extended end with a projecting lip having a 40 curved outline D'.

Having described my invention, what I claim as new, and desire to secure by Letters Patent, is—

25 The design for a sash-lock cam as herein shown and described.

In testimony whereof I affix my signature in presence of two witnesses.

WALKER MONROE.

Witnesses:

WILLIAM A. MILLER,
CLARA M. HUSS.
